UNITED STATES PATENT OFFICE

153,571

DESIGN FOR A RATTLE

Dee R. Givens, Western Springs, Ill.

Application May 8, 1947, Serial No. 138,915

Term of patent 7 years

(Cl. D34—15)

To all whom it may concern:

Be it known that I, Dee R. Givens, a citizen of the United States, and a resident of Western Springs, in the county of Cook and State of Illinois, have invented a new, original, and ornamental Design for a Rattle, of which the following is a specification, reference being had to the accompanying drawing, forming a part thereof.

Both sides of the handle are similar in appearance.

I claim:

The ornamental design for a rattle, as shown and described.

DEE R. GIVENS.
